UNITED STATES PATENT OFFICE.

EDWARD NELSON HALL, OF MEADVILLE, PENNSYLVANIA.

METHOD OF AND APPARATUS FOR FORMING PERMANENT WAVES.

Application filed July 13, 1927. Serial No. 205,490.

In treating hair to give it a permanent wave the common practice has been to coil the hair on a form, surround the hair with an enclosing pad carrying moisture, and heat this pad to a steaming point and thus act upon the hair to give it a permanent wave. This method involves some difficulty in that if the heating is carried too far and the moisture is entirely excluded the hair is often 10 burned. There is also the inconvenience of handling such high temperatures as are necessary in the heating elements which are locally applied. Further the number of elements which can be simultaneously applied 15 is somewhat limited. In the present invention these difficulties are obviated by generating the vapor, or steam independently of the different wave forming units and conveying it to the point of application and in 20 thus having the ability to control the quantity and temperature of the application and thus preventing excess temperatures and injury to the hair. This reduces the size of the units and permits of the simultaneous 25 application of a large quantity of them. It also provides a simple and convenient method for introducing the softening chemicals as these may be placed in the conduit and taken up by the initial moist steam and 30 be thus carried to the point of application. Features and details of the invention will appear from the specification and claims.

A preferred exemplification of the apparatus forming the subject matter of the invention and with which the method may be practiced is illustrated in the accompanying drawing as follows:—

Fig. 1 shows a sectional view of the generator with one of the units attached.

Fig. 2 an enlarged view of a unit in place.

1 marks the head having the growing or attached hair 2 which is to be waved.

A tube 3 is provided around which is coiled a strand of hair 4. The tube is provided with a head 5 in which is arranged a slot 6. This slot facilitates the fastening of a binding cord 7. The tube has discharge perforations 8 at the inner end.

A surrounding tube 9 of prepared paper 50 is provided and the inner end of the tube is closed by a clamp 10. Any suitable closure may be used, the clamp shown being a simple means of accomplishing this purpose. The outer end of the tube is connected by a joint 55 11 with a flexible tube 12 through which steam is delivered to the central tube 3.

The flexible tube is connected to a passage 13 leading from the steam chamber, or manifold 14. This manifold 14 has a large number of discharge passages 13 to which the tubes 12 may be attached and each passage is controlled by a needle valve 15, the needle valves being arranged radially around the chamber.

A generator 16 may be heated in any preferable manner but as shown by an electric heating element 17 supplied with current by line wires 18. Steam passes from the generator by way of a pipe 19 to a super-heated coil 20, the super-heated coil being electrically heated by an element 21 supplied with current by the lines 22. Steam passes from the superheater to the chamber 14.

In order to supply the hair with the proper softening chemicals, such as borax or sodium carbonate, a porous material impregnated with the softening material is arranged in the conduit passage, preferably in the tube 3. As shown this is a small brush similar to brushes ordinarily used for cleaning tubes. This brush is loaded with the softening material prepared in solution which adheres to the brush as it dries.

The steam leaving the chamber encountering the comparatively cold flexible tube becomes more or less moist and consequently is in condition to pick up the softening material in the form of a solution and carry it forward through the discharge passages 8 and into the hair. As the connections become hotter drier steam is delivered and the temperature, quality and quantity of the steam may be readily controlled at will. Under any ordinary conditions it is impossible to burn the hair as in the common methods and also the actual heat adjacent to the head is diminished, only the heat incident to carrying sufficient steam to accomplish the purpose being adjacent to the head.

While I have shown a preferable form of generator for the purpose of forming the steam and distributing it, I do not claim in this application the specific form of generator.

What I claim as new is:—

1. The method of forming permanent waves in attached hair which consists in confining and enclosing the hair in a wave-producing formation; generating the vapor at a point remote from the hair; superheating the vapor; and conveying the superheated vapor into the enclosed hair.

2. In an apparatus for forming permanent waves in attached hair, the combination of a conduit around which the hair may be coiled; an enclosing tube; a vapor generator; a superheater connected with the generator; and a flexible pipe extending from the superheater and supplying vapor to the space between the tube and conduit.
3. In an apparatus for forming permanent waves in attached hair, the combination with means for confining and enclosing the hair in wave producing formation, of a vapor generator, a superheater in communication therewith, and means for conveying the vapor from the superheater to the said hair confining and enclosing means.
4. In an apparatus for forming permanent waves in attached hair, the combination with means for confining and enclosing the hair in wave producing formation, of a vapor generator, a superheater in communication therewith, a manifold in communication with the superheater, and means for conveying the vapor from the manifold to the said hair confining and enclosing means.
5. In an apparatus for forming permanent waves in attached hair, the combination with devices for confining and enclosing the hair in wave producing formation, of a vapor generator, a super heater in communication therewith, and means for conveying the vapor from the superheater to the said hair confining and enclosing devices.
6. In an apparatus for forming permanent waves in attached hair, the combination with devices for confining and enclosing the hair in wave producing formation, of a vapor generator, a superheater in communication therewith, a manifold in communication with the superheater, and passages for conveying the vapor from the manifold to
- the said hair confining and enclosing devices.
7. In an apparatus for forming permanent waves in attached hair, the combination with devices for confining and enclosing the hair in wave producing formation, including perforated tubes around which the hair may be coiled and enclosures therefor, of a vapor generator, a superheater in communication therewith, and means for conveying the vapor from the superheater to the said tubes.
8. In an apparatus for forming permanent waves in attached hair, the combination with devices for confining and enclosing the hair in wave producing formation, including perforated tubes around which the hair may be coiled and enclosures therefor, of a vapor generator, a superheater in communication therewith, a manifold in communication with the superheater, and passages for conveying the vapor from the superheater to the said tubes.
9. In an apparatus for forming permanent waves in attached hair, a vapor generator, a superheater in communication therewith, and means for conveying the vapor from the superheater to the hair.
10. In an apparatus for forming permanent waves in attached hair, a vapor generator, a superheater in communication therewith, a manifold in communication with the superheater, and passages for conveying the vapor from the manifold to the hair.
11. The method of forming permanent waves in attached hair which consists in confining and enclosing the hair in wave producing formation, generating vapor at a point remote from the hair, superheating the vapor and conveying it to the hair.
- In testimony whereof I have hereunto set my hand.

EDWARD NELSON HALL.
